(57) **CLAIM**

The ornamental designs for a silicone divided plate, as shown, and described.

DESCRIPTION

FIG. 1 is a perspective view of a silicone divided plate; FIG. 2 is a top plan view thereof; FIG. 3 is a bottom plan view thereof; FIG. 4 is a right elevation view thereof; FIG. 5 is a left elevation view thereof; FIG. 6 is a front elevation view thereof; FIG. 7 is a rear elevation view thereof; and, FIG. 8 is a cross-section view taken from line 8-8 in FIG. 2. The broken lines in the drawings depict portions of the silicone divided plate that form no part of the claimed design.
